UNITED STATES PATENT OFFICE.

LEO JULIUS KROHN, OF GRAND JUNCTION, COLORADO.

ACCOUNT-FILE.

SPECIFICATION forming part of Letters Patent No. 697,092, dated April 8, 1902.

Application filed April 18, 1901. Serial No. 56,490. (No model.)

To all whom it may concern:

Be it known that I, LEO JULIUS KROHN, a citizen of the United States, residing at Grand Junction, in the county of Mesa and State of Colorado, have invented a new and useful Account-File, of which the following is a specification.

My invention relates to a file for filing accounts and other papers.

10 The object of it is, first, to furnish a means of keeping a set of accounts with a minimum amount of labor and mistakes, and also, second, to furnish a means for carrying the accounts around for collection without removing or recopying same by simply carrying file containing accounts in pocket. Account-leaves are readily removed or inserted in file. I attain these objects by the mechanism illustrated in the accompanying drawings, in which—

Figure 1 is a view of the file complete, except index-leaves, opened flat and ready for inserting account-leaves and index-leaves; Fig. 2, one of the index-leaves, the holes *e* and *f* of which fit on upright pegs *q* and *r* in Fig. 1; Fig. 3, top part of lock for holding leaves in file; Fig. 4, bottom part of lock for holding leaves in file; Fig. 5, file closed, edge view of side.

30 *a* and *b* in Fig. 1 represent two pieces of covered cardboard of equal size and of a size easily fitting in the coat-pocket, usually about four and one-half by nine inches, and bound together by a piece of cloth-covered elastic *c*, similar to garter or Congress-shoe welting, about two and one-half inches long and same length as width of covers *a* and *b*. The upright points *o* and *p* are sewed to elastic *c* near edge of cardboard or fastened otherwise by a plate into which they are fastened and which is covered over and which is represented by *m* in Fig. 3.

40 *q* and *r* represent nipples provided with screw-threads inside, into which the points *o* and *p* fit closely and hold securely by friction. Nipples *q* and *r* are also joined by a plate which is fastened to elastic and covered over. The pins *q* and *r*, *j* and *k* are hollow and contain screw-threads on their in-

50 sides for holding the upper unthreaded projections or points of the upper part of lock

by friction. The binding is of elastic fabric and is stretched on entering or removing leaves. The two parts of the lock are firmly sewed to the elastic, so that the points on upper part will fit into the hollow posts on bottom part. The sharp points or projections *o* and *p* are to perforate the paper filed, if desired, though ready-punched paper is usually provided for fitting the projections. *o* and *p* fit within *q* and *r* for their whole length. Paper for file is same size of index-leaf, Fig. 2, except tab *g*, which tab extends even with bottom edges of covers of file, (*a* and *b*, Fig. 1.) *e* and *f*, Fig. 2, (index-leaf) are holes in index-leaf to fit projections *q* and *r* in Fig. 1. Account-pages are perforated all the way across about a half-inch below punched holes, so that when a person pays an account in full the account is torn out and handed to him, thus balancing the account.

Fig. 3 represents a view of the top part of lock detached from file. Fig. 4 represents a view of the bottom part of lock detached from file.

75 The two parts of lock may be fastened to covers, as described under Fig. 1, or they may be inserted from outside of covers (when closed) through holes in elastic to fit same, so that they can be removed separately from covers.

Projections *h* and *i*, Fig. 3, and *j* and *k*, Fig. 4, are at right angles to plates *m* and *n* and fastened to same by screw-threads through plates and on butt-ends of projections.

85 I am aware that indices similar to ones described have been used, and I do not claim them as my invention; but

What I claim, and desire to secure by Letters Patent, is—

90 In an account-file, two covers bound together by an elastic fabric, said fabric forming also a back for the file, and a pair of telescoping pins mounted near the opposite edges of said fabric and adjacent to the covers.

95 In testimony whereof I have signed my name to this specification in the presence of two subscribing witnesses.

LEO JULIUS KROHN.
